UNITED STATES PATENT OFFICE.

FRANK S. JONES, OF PHILADELPHIA, PENNSYLVANIA.

POWER DRIVING MECHANISM.

Application filed December 28, 1920. Serial No. 433,727.

To all whom it may concern:

Be it known that I, FRANK S. JONES, a citizen of the United States, residing at Philadelphia, in the county of Philadelphia and State of Pennsylvania, have invented 5 certain new and useful Improvements in Power Driving Mechanism, of which the following is a specification.

One object of my present invention is to 10 provide an improved power driving mechanism for use in connection with the feed mechanism of large slotters such as my improved slotting machine forming a part of my co-pending application for U. S. patent, 15 Serial No. 378,146. For example the improved mechanism of my present invention can be used with particular advantage for operating the work table and carriage of said latter slotting machine by power derived 20 from the machine so that a workman can quickly move said table into the proper position to "set up" the work ready for the cut.

Another object of my present invention 25 is to so construct my improved mechanism that it can be readily operated from either side of the base of the machine so that a workman can easily control it from either side of the base of the machine whereby 30 the workman is not compelled to walk from one side of the machine to the other in order to start or stop the mechanism.

Another object is to make my invention in 35 a comparatively simple and durable manner.

These objects, and other advantageous ends which will be described hereinafter, I attain in the following manner, reference being had to the accompanying drawings in 40 which

Figure 1 is a fragmentary side elevation showing my improved power driving mechanism connected to a slotting machine of the character described and illustrated in my 45 above mentioned co-pending application for patent,

Figure 2 is a fragmentary transverse sectional elevation illustrating the lever control for the mechanism of my present invention,

Figure 3 is a section taken on the line 3—3 of Figure 5, illustrating my present invention and drawn on a larger scale than the illustration of said present invention in 55 Figure 1,

Figure 4 is a section taken on the line 4—4 of Figure 5,

Figure 5 is a section taken on the line 5—5 of Figure 3, and

Figure 6 is a section taken on the line 6—6 of Figure 3.

Referring to the drawings, 7 represents a large slotting machine such as described in my above mentioned co-pending application for patent and which includes a shaft 8 65 which when rotated effects the rotation of the work table 9 and the transverse movement of a carriage 10 which supports the work table 9. The above mentioned elements do not in themselves form a part of 70 my present invention since they are covered in my above mentioned co-pending application and receive operative power during the slotting action of the machine due to the movement of a link 11 which imparts motion to a ratchet wheel 12 through the medium of a pawl 13 on said link 11. It is necessary however in order to "set up" the 75 work with respect to the cutting parts of the slotter to move the carriage and work table 80 so as to bring the work in proper relative position with respect to the cutting elements and my improved mechanism of my present invention is adapted to rotate, by power derived 85 from the machine, the shaft 8 in order that the carriage and work table can be quickly moved into a desired position.

My present invention includes a casing 14 which has a bracket extension 15, as shown in Figures 5 and 6, for attachment 90 to the base 16 of the slotting machine. This casing at one end provides a bearing 17 for a hub 18 of a gear wheel 19; said gear wheel being positioned within the casing 14 adjacent one end thereof. The hub 18 is 95 rigidly secured to one end of the shaft 8 in the present instance by a pin 20. A second gear wheel 21 is mounted within the casing 14 adjacent the opposite end and is opposed to the gear wheel 19. The gear wheel 21 has a hub 22 mounted in a bearing 23 provided by the casing 14 opposite the bearing 17. A primary shaft 24 has a bearing in the hubs 18 and 22 and is freely rotatable with respect thereto. This primary shaft has a 100 portion which extends outside of the casing and to which is attached a pulley 25; said pulley being operatively connected by a belt 26 with the motor 27 which is also used for the purpose of operating other 105 110

parts of the slotting machine. The gear wheel 19 has an inwardly tapering cavity providing a frusto-conical friction clutch surface 28 and the gear wheel 21 has a cavity 5 providing a frusto-conical friction clutch surface 29. A clutch collar 30 is slidably keyed to the primary shaft 24 and has opposed clutch portions 31 and 32 which are respectively normally out of engagement 10 with the clutch surfaces 28 and 29 of the wheels 19 and 21. However the construction is such that when the clutch collar 30 is moved in one direction along the shaft 24, the clutch portion 32 will engage the surface 15 face 29 and rotate the wheel 21.

Two short shafts 33 and 34 have bearings in the casing 14 below the wheels 19 and 21. A wide face intermediate pinion 35 is secured on the shaft 33 and meshes with the gear wheel; this intermediate pinion being hereinafter termed the primary intermediate pinion. 20

The primary intermediate pinion 35 meshes with a secondary intermediate pinion 36 which is secured to the shaft 34 and the secondary intermediate pinion 36 meshes with the gear wheel 19. A clutch operating lever 37 is pivoted at 38 in the casing 14 and has a portion 39 which engages in a 25 groove 40 in the clutch collar 30. The clutch lever 37 has an arm 41 which projects upwardly out of the casing 14 and is connected by a link 42 with the lower end of a hand-lever 43; said hand-lever being secured to a shaft 44 which extends transversely from one side of the machine to the other and at its opposite end this shaft 44 has another hand-lever 43^a secured thereto. Thus by moving either of the hand-levers 43 or 40 43^a, the link 42 can be moved to swing the clutch lever 37 on its pivot 38 so as to slide the clutch collar 30 in opposite directions along the primary shaft 24.

In the operation of my improved mechanism, considering that the shaft 24 is rotating constantly in one direction, if the clutch collar is moved into driving engagement with the wheel 19, the shaft 8 will be driven in the direction of the shaft 24 and the work table and carriage will be moved in a direction dependent upon said direction of movement of the shaft 8. If, on the other hand, the clutch collar 30 is moved longitudinally in an opposite direction so as to engage the wheel 21, the wheel 21 will rotate the primary pinion 35 and this motion will be imparted through the secondary pinion

36 to the wheel 19 and the wheel 19 will be rotated in a direction opposite to the direction of rotation of the primary shaft 24 and since the wheel 19 is directly connected through its hub 18 to the shaft 8, the shaft 8 will be rotated in a direction opposite to the direction of rotation of the shaft 24 and the work table 9 and carriage 10 will be correspondingly moved in a direction opposite to that in which it is rotated when the clutch collar directly drives the wheel 19. Thus a workman by a manipulation of either of the hand-levers 43 or 43^a can effect the movement of the carriage and work table in either direction and in this manner the work of the machine is facilitated and expedited. 70

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claim. 80

Having thus described my invention, what I claim as new and desire to secure by Letters Patent is:—

A power driving mechanism including a casing; a driving shaft extending into said casing; a gear wheel rotatably mounted on said driving shaft and having a hub mounted in said casing, said gear wheel having a clutch face; a collar on said driving shaft for holding said gear wheel in position; a driven shaft; a gear wheel having a hub rotatably mounted in said casing and connected to said driven shaft and having a clutch face; a clutch member keyed to the driving shaft and adapted to engage either clutch face; parallel shafts mounted in said casing; an intermediate gear mounted on one of said shafts and meshing with the gear on the driving shaft; and a second intermediate gear mounted on the other shaft, overlapping and meshing with the first named intermediate gear and with the gear on the driven shaft; substantially as described. 100

In testimony whereof I have signed my name to this specification in the presence of two subscribing witnesses.

FRANK S. JONES.
